(57) **CLAIM**

The ornamental design for a floor lamp, as shown and described.

DESCRIPTION

FIG. 1 is a perspective view of a floor lamp showing my new design;

FIG. 2 is a front plan view thereof;

FIG. 3 is a side elevational view thereof;

FIG. 4 is a top plan view thereof; and,

FIG. 5 is a bottom plan view thereof.

The broken-line disclosure in the views is understood to represent a portion of the article in which the claimed design is embodied, but which forms no part of the claimed design.
